UNITED STATES PATENT OFFICE

FRED C. ANDERSEN, OF BAYPORT, AND EARL C. SWANSON, OF STILLWATER, MINNESOTA, ASSIGNORS TO ANDERSEN FRAME CORPORATION, OF BAYPORT, MINNESOTA, A CORPORATION OF WISCONSIN

WINDOW AND DOOR FRAME

Application filed December 30, 1929. Serial No. 417,421.

The object of our invention is to provide a window or door frame with provision for mounting each jamb on the sill without the necessity of nailing as the parts of the frame 5 are being assembled.

A further object is to provide a means for joining the sill and the jambs together, which will not only hold them firmly in their proper relative position, but will provide means for 10 conducting rain or the water of melting snow or ice outwardly on the sill and away from the window frame and the wall of the building.

A further object is to provide a means for joining the sill and jambs together, which will 15 be comparatively simple and not add materially to the expense of the frame while presenting a substantial appearance thereto.

Other objects of the invention will appear 20 from the following detailed description.

The invention consists generally of various 25 constructions and combinations, all as hereinafter described and particularly pointed out in the claims.

In the accompanying drawings forming a part 30 of this specification,

Figure 1 is a plan view of a sill embodying our invention;

Figure 2 is a perspective view of the same;

Figures 3 and 4 are perspective views showing 35 the lower portion of the jambs in position to engage the sill;

Figure 5 is a perspective view showing the sill and jambs in their assembled relation;

Figure 6 is an end view of the sill showing 40 its relative position with respect to the jamb when the parts are assembled;

Figure 7 is a sectional view on the line 7—7 of Figure 6;

Figure 8 is a plan view of one end of a sill showing a slightly modified construction;

Figure 9 is an inside view of the jamb adapted to fit the sill of Figure 8;

Figure 10 is a horizontal sectional view 45 through the jamb as mounted on the sill;

Figure 11 is an end view of the sill and jamb assembled;

Figure 12 is a sectional view on the line 12—12 of Figure 11;

Figure 13 is a plan view of one end of the 50 sill showing a slight modification of the sill of Figure 8;

Figure 14 is a view of the inner face of a jamb adapted for this construction of sill;

Figure 15 is a horizontal sectional view 55 through the jamb in position on the sill;

Figure 16 is an end view of the sill and the outer face of the jamb; and

Figure 17 is a sectional view on the line 60 17—17 of Figure 16.

In the drawings, 2 represents a window sill having preferably the usual end notches 3 and the raised upper portion 4 and the horns 5 at each end of the sill. 6 is a shoulder at the inner edge of the sill and 7 represents 65 notches formed in the inner edge of the sill from which transverse dados 8 extend through the raised portion 4 to a point adjacent the outer edge of the sill. A continuation 9 of the shoulder 6 is formed on the 70 raised sections 10 provided on the upper surface of the sill between its vertical end faces and the dados 8. These dados are of suitable width and preferably correspond in depth to the raised portion 4 of the sill so 75 that the floor or bottom of each dado is on a line and forms a continuation of the upper surface of the sill between the raised portion 4 and the outer edge. The sill when set in the frame will be downwardly and outwardly inclined as usual in window and door frame construction and moisture from rain or melting snow or ice accumulated in and around the dados will be directed thereby outwardly away from the inner portion 80 of the window and the walls of the building.

11 represents the jambs, provided one at each end of the sill. As here shown, particularly in Figure 7, the lower end of the jamb is 85 adapted to enter and slide in the sill dado 90

filling it substantially from side to side, the lower end of the jamb preferably corresponding in thickness to that part above the sill, the end of the jamb being simply squared and fitted to the dado or transversely grooved as shown in Figure 9. A notch 12 is preferably formed in the lower end of each jamb extending partially there across and forming a depending tongue or extension 13, the notch 12 having a continuation 14 into the depending tongue and of suitable size to receive the edge of the sill when the jamb and sill are assembled. The formation of this recess in the tongue 13 provides a neck 15 which preferably corresponds in thickness to the depth of the notch 7 in the sill so that when the jambs and sill are assembled with the lower end of each jamb fitting snugly into its dado in the sill, the inner edge of the jamb will be flush substantially with the corresponding edge of the sill as shown plainly in the assembled view, Figure 5. The usual parting bead 16 is provided in the inner face of each jamb and a blind stop 17 having a notch 18 at its lower end is provided at the outer edge of each jamb and is adapted, when the parts are assembled, to assume the position shown in Figure 5. The outer face of the blind stop will then be substantially flush with the corresponding edge of the raised portion 4 of the sill.

The recess 14 formed in the depending tongue 13 of each jamb will allow the lower portion of this tongue to extend in under the edge of the sill as plainly shown in Figure 6 so that when the parts are assembled, the sill and jamb will be firmly locked together and may be further secured by nailing through the neck portion 15 of each jamb into the sill or in any other suitable way. In Figure 8 a deeper recess 7^a is provided in the inner edge of the sill at each end and the shoulder 6 has gains 19 adjacent the dado 8^a. The jamb 20 has a tongue 21 formed on the lower end adapted to enter and slide in the dado 8^a while the shoulder 22 formed by the tongue passes through the gain 19 and slides on the upper surface of the raised portion of the sill. At the inner edge of the jamb a liner strip 23 may be provided instead of forming a tongue on the inner edge of the jamb and the lower end 24 of this liner strip depends below the edge of the jamb and is adapted to enter the notch 7^a and be seated snugly against the inner edge of the sill as clearly illustrated in Figure 11. The inner liner strip as shown in Figure 10, forms a continuation of the jamb and is used to build up this inner edge and avoid the necessity of using a wider piece of lumber for the jamb itself.

The usual blind stop 17^a is provided at the outer edge of the jamb with a recess in its lower end to provide a continuation of the tongue 21 and adapt the jamb for slid-

ing into the dado and fitting snugly on the surface of the sill.

In Figure 13, notches 7^b and 7^c are provided in the inner edge of the sill at each end and the jamb 20^a has the tongue 21^a at its lower end corresponding to the one shown in Figure 12, while the inner liner strip 23^a extending down below the jamb has a recess 25 that is adapted to receive the inner edge of the sill and interlock therewith so that the jamb and sill will be held firmly together, the liner strip 23^a being of suitable thickness so that when the sill is inserted into the recess in the strip, the inner face of the strip will preferably be flush substantially with the edge of the sill as shown plainly in Figure 15. The usual blind stop 17^c is provided at the outer edge of the jamb and the parting bead 16^a is also provided intermediate to the inner and outer edges of the jamb.

These modifications in the manner of mounting the window and door frame jambs on the sill, provide extremely convenient means for easily and quickly assembling the elements of the frame, all without adding materially to the expense of manufacture. A joint such as we have shown and described between the jambs and the sill, not only aids in holding the parts firmly together, but tends to exclude moisture from passing through these joints into the wall of the building and any accumulation of moisture in or around the joints and entering the dados will be conducted thereby to the outer side of the sill. We have described one jamb and one end of a sill but the other end of the sill and the other jamb will be a substantial duplication and while we have shown and described a window frame it will be understood that the invention is equally applicable to and may be readily incorporated in the construction of a door frame.

We claim as our invention:

1. A sill having a transverse dado in its upper surface and a notch intersecting the inner end of the said dado, a jamb having a lower end corresponding substantially in thickness to the width of said dado and fitting therein, said jamb having a depending part to enter the notch in said sill and said depending part being provided with a recess, the lower end of the jamb forming the upper wall of the recess and adapted to enter said dado and the lower wall of said recess being seated against the under surface of the sill when the sill and jamb are assembled, the rear lower portion of the jamb back of the recess forming a neck adapted to receive a nail to hold the jamb and sill together.

2. A sill having a transverse dado in its upper surface and a notch in the longitudinal edge of said sill intersecting the inner end of said dado, a jamb having a lower end corresponding substantially in thickness to the

width of said dado and fitting therein, said jamb having a depending part at one edge provided with a transverse recess, the inner vertical wall of which is seated against the corresponding wall of said notch when the 5 sill and jamb are assembled, the lower face of said recess abutting the inner wall of said notch on the under side whereby said sill and jamb will be locked in their assembled relation.

10 In witness whereof, we have hereunto set our hands this 21st day of December, 1929.

FRED C. ANDERSEN.
EARL C. SWANSON.
